UNITED STATES PATENT OFFICE

PHILIP S. WALKER, OF MANSFIELD, MASSACHUSETTS

FEED FOR SELF-FILLING FOUNTAIN PENS

Application filed January 9, 1929. Serial No. 331,268.

This invention relates to an improvement in feed for self-filling fountain pens.

In all or nearly all self-filling fountain pens heretofore made, so far as known to me, in order to fill the ink sac of the pen it has been necessary to dip not only the pen but the end of the holder as well into the ink during the filling and this necessitates wiping the ink from the holder after it is filled. One object of the present invention is to provide such a construction that in order to fill the pen, only the projecting portion of the feed which extends beyond the holder need be immersed in the ink without immersing any part of the holder itself.

In all other self-filling fountain pens heretofore made so far as known to me the feed has been provided with two ink passages through one of which the ink is drawn into the holder or sac during the filling of the pen and through the other of which the ink flows from the sac to the pen point or nib when the pen is used in writing.

One object of the present invention is to so construct the feed that the same ink passage through which the ink is drawn when filling the reservoir in the holder serves also as the passage through which the ink is fed from the reservoir to the nib of the pen when writing.

Another feature of the invention consists in the construction of the feed with a transverse groove to provide the vent whereby the ordinary vent hole in the nib of the pen may be dispensed with.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto ap-

pended or the requirements of the prior art.

In the drawings:

Fig. 1 is a longitudinal sectional view on an enlarged scale of the forward portion of a fountain pen having a feed embodying the invention.

Fig. 2 is a section on line 2—2, Fig. 1.

Fig. 3 is a plan view on an enlarged scale of a feed embodying the invention.

Fig. 4 is a side elevation of the feed shown in Fig. 3.

Referring now to the drawings, the barrel section 11 of the fountain pen has a tubular pen section 14 which fits in its forward end. An ink sac 13 is attached to the rear end 65 of said pen section.

The feed which is the special subject of the invention is shown as a whole at A. Preferably the feed is a unitary structure. The rear portion 20 of the feed is cylindrical and is of somewhat less diameter than the outer portion of the bore of the pen section 14 so that when the feed is inserted in the end of the pen section 14 there will be a thin space 70 as shown at 19 between the periphery of the feed and the inner periphery of the pen section. The inner end portion 19^a of the bore of the pen section is of less diameter than the outer portion thus forming a shoulder 20^a 75 which serves as a seat for the rear end of the feed.

The portion of the feed which projects outside of the feed end of the pen section is flattened or partially cut away on one side 80 as shown at 21. On the face of the projecting portion on the opposite side from the flattened face 21, there is formed a groove or depression 22 extending parallel to the axis of the feed but stopping some distance short of the forward end of the feed as clearly shown 85 in Figs. 1, 3 and 4.

The said pen section is formed with a longitudinal passage 23 open at its rear end to the passage 19^a in the pen section and extending forward part way through the reduced forward end portion of the feed, thence it turns laterally and at 24 opens into the longitudinal groove or depression 22 in the face of the feed. The only outlet from said passage 90 95 100

23 is through the aperture 24 leading to the depression 22.

5 A transverse semi-circular groove 25 crosses the longitudinal depression 22 slightly forward of the outlet aperture 24 and extends around to the flattened lower side 21 of the feed. The groove 25 therefore communicates through the depression 22 with the outlet aperture 24 of the longitudinal passage 23, 23^a in the feed.

10 Preferably the forward portion 23^a of the passage 23 is reduced in diameter from that of the rear portion as will be seen from the drawings.

15 The shank portion of the pen B should be inserted in the thin space between the projecting portion of the convex side of the feed and the inner wall of the pen section 14 as clearly shown in Fig. 1.

20 The nib end of the pen is formed with the usual split 26, and when the pen is inserted this split intersects the transverse groove 25 and the longitudinal depression 22 of the feed. By reason of the transverse groove 25 sufficient vent is given for the feed so that the hole usually formed in the nib of the pen connecting with the longitudinal split may be entirely omitted.

25 While I have shown and described one form of holder and barrel of a fountain pen, it is to be understood that this is illustrative of one form only and that the invention is not limited to use with that particular type of holder. Any other suitable form of holder 30 for use with the feed described may be employed.

35 What I claim is:

1. A feed for a fountain pen of the self-filling type having a longitudinal passage open at the rear end of the feed and extending wholly within the wall of the feed until it reaches a point somewhat back from the forward end of the feed, thence turning laterally and opening out through the pen supporting side of the feed, the said feed being also formed with a longitudinal recess in its upper face intersecting said outlet from the longitudinal inside passage, said longitudinal recess being walled at its sides and ends, said feed being formed with a flattened underside opposite said recess and being also formed with a transverse peripheral groove extending from both sides of said longitudinal recess to the outer edge of the flattened underside of said feed.

2. A fountain pen of the self-filling type having a barrel, a tubular pen section connected with the front end of the barrel, in combination with a feed member connected with the forward end of said pen section, said feed member having a longitudinal passage communicating at its rear end with the passage in said pen section and extending forward wholly within the wall of the feed until it reaches a point somewhat back from

the forward end of the feed member, thence turning at an angle and opening out through the pen-supporting side of the feed at some distance back from the forward end of the feed, the face of the feed on the pen-supporting side having a longitudinal depression into which said outlet from said longitudinal passage opens, said feed having a transverse groove which intersects said longitudinal depression and is open at its ends, 70 said longitudinal depression being walled at both ends and at its sides except where it intersects said transverse groove, said transverse groove constituting the ink inlet in filling the pen.

3. A fountain pen of the self-filling type having a barrel and a tubular pen section connected with the front end of the barrel, in combination with a feed member connected with the forward end of said pen section, 80 said feed member having a longitudinal passage communicating at its rear end with the passage in said pen section and extending forward wholly within the wall of the feed until it reaches a point somewhat back from 90 the forward end of the feed member, thence turning at an angle and opening out through the pen-supporting side of the feed at some distance back from the forward end of the feed, the face of the feed on the pen-supporting side having a longitudinal depression into which said outlet from said longitudinal passage opens, said feed having a transverse groove which intersects said longitudinal depression and is open at its ends, 95 said longitudinal depression being walled at both ends and at its sides except where it intersects said transverse groove, the ends of said transverse groove being spaced apart from each other and open to the air, said transverse groove 100 constituting the ink inlet in filling the pen.

In testimony whereof I affix my signature.

PHILIP S. WALKER.
